UNITED STATES PATENT OFFICE

GEORGE WILLIAM COIN, OF MANHATTAN, KANSAS

AIR REFRIGERATING DEVICE

Application filed May 12, 1932. Serial No. 610,944.

The present invention relates to an apparatus for cooling the air in rooms and the like and the objects of the invention are to provide a portable device of this nature which is light and simple in construction compact, thoroughly efficient and reliable in use and otherwise well adapted to the purpose for which it is designed.

With the above and numerous other objects in view as will appear as the description proceeds, the invention consists in certain novel features of construction, and in the combination and arrangement of parts as will be hereinafter more fully described and claimed.

In the drawings:

Figure 1 is a side elevation of a device embodying the features of my invention.

Figure 2 is a horizontal section therethrough taken substantially on line 2-2 of Figure 1.

Figure 3 is a longitudinal vertical section therethrough taken substantially on line 3-3 of Figure 2.

Figure 4 is an end elevation thereof, and

Figure 5 is an opposite end elevation thereof.

Referring to the drawings in detail it will be seen that numerals 5 denote four rectangular cork insulated walls of a casing one wall of which is provided with an opening 6 in which is disposed a cork insulated door 7. Numeral 8 denotes a rectangular tube disposed inside the walls 5 and having outwardly flared ends 9 and 10 fixed to the ends of the walls 5. A plurality of vertical and horizontal partitions 11 are provided in the flared end 10 for distributing the air. A fan blower 12 is mounted in the end 9. The space between the walls 5 and the tube 8 provides an ice chamber, cracked ice being placed therein through the opening 6. Obviously when the propeller or fan blade 12 is in operation air will be forced through the tube 8 and cooled and then distributed by the distributing partitions 11 of the flared end 10. Inside the tube 8 are a plurality of baffles 14. Numeral 15 denotes a drain cock for draining off the water from the ice compartment.

It is thought that the construction, opera-

tion, utility and advantages of this invention will now be quite apparent to those skilled in this art without a more detailed description thereof.

The present embodiment of the invention has been described in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. An air refrigerating device of the class described comprising a casing including four insulated walls, a tube inside the walls and spaced inwardly therefrom, said tube being formed with outwardly flared ends fixed to the ends of the walls, a plurality of horizontal and vertical partitions in one of the flared ends.

2. An air refrigerating device of the class described comprising a casing including four insulated walls, a tube inside the walls and spaced inwardly therefrom, said tube being formed with outwardly flared ends fixed to the ends of the walls, a plurality of horizontal and vertical partitions in one of the flared ends, a plurality of baffles in the tube.

In testimony whereof I affix my signature.

GEORGE WILLIAM COIN.
